Attorney

UNITED STATES PATENT OFFICE.

CODY LYON, OF EMMETT, IDAHO.

INSULATOR FOR ELECTRIC WIRES.

1,217,032.

Specification of Letters Patent. Patented Feb. 20, 1917.

Application filed August 11, 1915. Serial No. 44,935.

To all whom it may concern:

Be it known that I, CODY LYON, a citizen of the United States, residing at Emmett, in the county of Gem and State of Idaho, have invented certain new and useful Improvements in Insulators for Electric Wires, of which the following is a specification, reference being had to the accompanying drawings.

10 My invention relates to insulators for electric wires, and particularly to insulators of that type wherein the head of the insulator is formed with a receiving kerf and wire engaging kerfs acting to hold the wire in place upon the insulator.

The general object of my invention is the provision of a simple, cheaply made, readily applied, and thoroughly effective insulator of this type, so constructed that the 20 wire when turned at right angles to the entrance kerf or when the insulator is turned at right angles with relation to the wire, the wire will be held securely in position upon the insulator without the necessity of 25 binding wires.

Other objects will appear in the course of the following description.

My invention is illustrated in the accompanying drawings, wherein:

30 Figure 1 is a perspective view of my improved insulator attached to the cross arm of a telegraph pole;

Fig. 2 is an end elevation partly in section;

25 Fig. 3 is a side elevation partly in section;

Fig. 4 is a horizontal sectional view taken on the plane of the kerfs 10 and 11.

Referring to these figures, 2 designates an 40 insulator made of any suitable material such as glass, porcelain, or other non-conductor having a base 3 formed with oppositely disposed downwardly extending flanges 4 adapted to engage over the cross arm A

45 of a telegraph pole and to be held thereto in any suitable manner as by screws 6 which pass through notches or grooves 5 formed in the side face of the base. This insulator is formed with a bulbous head 7 and this

50 head as illustrated in Fig. 1 is formed with a transversely extending kerf or slot 8 which

extends downward to the middle of the head. Intersecting this slot 8 are the locking slots 9 and 10. These slots are cut inward from the corners of the head on opposite sides 55 and have a staggered relation to each other. These slots 9 and 10 overlap each other at their inner ends and also intersect the slot 8. As a consequence a wire inserted in the slot 8 and then turned at right angles to 60 the head so as to be disposed within both of the slots 9 and 10 will be interlocked with the head and cannot be lifted up nor moved laterally with relation to the head.

It will be obvious, of course, that instead 65 of turning the wire designated 11 at right angles to the kerf 8 the insulator may be turned with relation to the wire so as to bring the slot 8 at right angles to the wire 11. It will thus be seen that there is no 70 necessity of using binding wires for holding the wire 11 to the insulator, that the wire 11 will be securely engaged with the insulator under all circumstances and cannot be detached therefrom after the wire 75 has been stretched, and that even if the wire is slack it will not easily become detached from the insulator inasmuch as it must be turned at right angles to the ends of the slots 9 and 10 in order that it shall pass out 80 through the slot 8.

Having thus described my invention, what I claim is:

An insulator for electric wires comprising a base and a head, the head having a vertically disposed transverse entrance slot and oppositely disposed horizontal slots in staggered relation to each other, the horizontal slots overlapping each other and intersecting the vertical slot, the base having laterally disposed flanges adapted to embrace the cross arm of a telegraph pole, the side walls of the base between said flanges being formed with vertical grooves for engagement with fastening devices. 90

In testimony whereof I hereunto affix my signature in the presence of two witnesses.

CODY LYON.
